ELECTRIC FUSE

Morris B. Wood, Newburyport, Mass., assignor
to The Chase-Shawmut Company, Newbury-
port, Mass., a corporation of Massachusetts

Application March 13, 1934, Serial No. 715,304

12 Claims. (Cl. 200—121)

This invention relates to electric fuses wherein the readily fusible portion of the fusible element or fuse link underlies a window in the fuse casing and wherein an end cap retains the transparent window in place and is crimped or bent about a flange of the insulating casing. The invention particularly relates to electric fuses of the screw plug type.

A plug type of fuse is adapted to be screw-threaded into a base or receptacle and is used largely for the protection of the various circuits of a house. The fuse bases in the house circuits are frequently installed in groups in cellars, closets and other relatively dark localities where the intensity of light is so low that it is difficult to determine the condition of the fusible element of the usual plug fuse, that is, to determine whether or not the fuse has blown. It often happens that when one of the fuse circuits is interrupted, a large number of the fuses of a group have to be tested to locate the blown fuse, since the available light is insufficient to enable the blown fusible element of the group of the usual fuses to be surely located.

An object of the present invention is the provision of an electric fuse of the type above set forth wherein the interior of the fuse casing that underlies the more readily fusible portion of the fusible element is white in color and wherein the fusible element or link at and adjacent the more readily fusible portion thereof is black so that the more readily fusible portion contrasts with and thus stands out prominently against the white background provided by the white interior of the fuse chamber of the casing, whereby the condition of the fusible element can be observed readily even in dull light.

A further object is the provision of a fuse chamber having tapered white walls that converge toward the bottom of the chamber so that the light admitted into the large open end of the chamber can be reflected into the bottom of the chamber to illuminate it and cause it to contrast more prominently with the black non-reflecting fusible element that it underlies.

Considerable pressure may be generated within the fuse chamber when the heavily-overloaded fusible element blows and a further object of the invention is the provision of a fuse plug having an improved construction for venting the fuse chamber and relieving the pressure in a manner that is free from fire hazard.

A yet further object is generally to improve the construction of electric fuses.

Fig. 1 is a side elevation of an electric fuse of

the plug type embodying the present invention.

Fig. 2 is a plan view of the fuse of Fig. 1.

Fig. 3 is a sectional elevation taken along line 3—3 of Fig. 2.

Fig. 4 is a detail showing a portion of the gas 5 venting channels and cap-locking teeth of the head flange of the fuse body.

Fig. 5 is a sectional detail taken along line 5—5 of Fig. 3 and illustrating the manner in which the end cap overlies and interlocks with 10 the cap-locking teeth and venting channels.

Fig. 6 is a plan view of a fusible element or fuse link embodying the present invention.

Fig. 7 is a plan view of a strip of fusible metal from which the fusible element of Fig. 6 is 15 severed.

Fig. 8 is a view similar to Fig. 6 but illustrating a modified form of fusible element.

Fig. 9 is a plan view similar to Fig. 2 but illustrating the appearance of a blown fusible ele- 20

The plug fuse embodying the present invention comprises the generally cylindrical insulating body 10 formed of dry process porcelain having the fuse chamber 12 therein open at the top of the 25 body and closed at the bottom by a transverse wall 14 which is integral with the side wall of the body. The exterior cylindrical surface of the body 10 is provided with outstanding spirally disposed ridges 16 forming external screw threads 30 on which an externally and internally screw-threaded metal shell 18 is screw-threaded, which shell constitutes the outer terminal or contact member of the fuse. The fuse body is provided with a center contact 20 in the form of a tubular 35 rivet having a head 22 which overlies the middle portion of the outer face of the bottom wall 14 and a shank 24 which is extended through a passage in the bottom wall and is suitably secured therein as by upsetting the inner end of the shank. The 40 shank has a recess therein which receives one end of a fusible element or fuse link 26, which end is electrically and mechanically connected to the center contact by a body of solder 28. The other end of the link extends through a passage 30 in 45 the fuse body to a position behind a portion of the shell 18 and is anchored to said shell by a body of solder 32 which also anchors the shell against rotation on the porcelain body. The upper or head end of the insulating body 10 is 50 provided with a peripherally outstanding continuous flange 34 the lower face 36 of which is inclined or slopes toward the cylindrical shell-bearing portion of the body and is formed, preferably completely about its circumference, with a plu- 55

rality of gas-venting channels 38 and interposed cap-locking teeth 40, both of which are inclined toward the shell-bearing portion of the insulating body. A clear transparent mica disc 42, comprising a window overlies the top of the body 10 and the opening of the fuse chamber 12 and is disposed within a metal end cap 44. Said end cap has an end wall 46 which overlies the transparent window disc 42, a cylindrical wall 48, preferably 5 knurled or having corrugations 50, which closely surrounds and encloses the cylindrical side wall of the flange 34, and an inturned flange or wall 52 which is parallel with the end wall 46 and confronts the inclined wall 36 of the flange 34, and 10 the teeth 40 and channels 38 thereof. The flange 52 preferably is not in contact with the wall 36 except at the inner edge of the flange so that there is an annular channel 54 between the flange and the wall. At its inner edge, the flange 52 is forced 15 into the channels 38, as indicated in Figs. 1, 3, and 5, sufficiently to form a series of raised portions or ridges 56 which receive the apices of the teeth 40 by which the end cap is locked against rotation on the insulating body 10. The venting 20 channels are open under the inner edges of the flange 52 so that excessive gas pressure within the fuse chamber 12 can be vented through said channels and a passage between the outer face of the fuse body and the transparent window 42 25 and the side wall 48 of the end cap, which passage is formed by the high chamber pressure and the expansion of the end cap, permitted largely by the construction of the end flange 52 and its spaced relation with the inclined end face of the 30 flange 34, which allows the end flange to flex upon abnormal chamber pressures.

The end wall 46 of the end cap has an opening 58 which preferably is the full diameter of and is aligned with the fuse chamber 12 and through 40 which the interior of the chamber is visible.

The fusible element 26 has an intermediate section 60 which is disposed immediately under the opening 58 and the window 42 and is generally parallel therewith and perpendicular to the end 45 portions that are connected to the fuse terminals. Said intermediate portion 60 contains a more readily fusible section 62 usually of reduced cross-sectional area as by being formed by the opposed notches 64 in the opposite edges of the fusible element, or otherwise. In Fig. 8 the more readily fusible section 62a is obtained by an aperture 64a 50 in the fuse. The more readily fusible section 62, for the type of fusible element herein illustrated, is located usually in the middle of the element and is ruptured upon current overload, thereby to interrupt the circuit including the fuse. On moderate overloads, especially, the line of 55 fusion of the ends of the fusible element at the more readily fusible section 62 is narrow. On heavier overloads the line of fusion may be broader. It is an object of this invention to provide a marked and relatively great contrast between the fusible element and the background against which it appears when viewed through the window 42 60 so that the condition of the fusible element, and the presence of a ruptured line, if there is one, can be readily observed even when the fuse is in dull light and the observer is some distance therefrom. The fuse body 10 is made of a dry process 65 porcelain and is practically pure white and hence the inner wall 66 of the fuse chamber thus is readily visible even when the illumination thereof is poor, as when the fuse is in a poorly illuminated locality. The porcelain surface 66 has an 70 apparent crystalline appearance that enhances its 75

response to illumination. The bottom of the fuse chamber 12 is occupied by a body of cement 68, or the like, as plaster of Paris or other material that is white, which overlies and conceals the center contact so that the entire surface of the fuse 5 chamber presents a uniformly white appearance. The fuse chamber 12 is tapered inwardly or the wall 66 thereof slopes from the open end toward the bottom of the chamber so that the chamber is smaller in diameter at the bottom than at the 10 top. Thus light admitted through the window 42 is reflected from upper portions of the sloping side wall 66 downwardly to the bottom of the fuse chamber so that the entire inner surface of the 15 chamber is practically equally brilliantly illuminated.

The fusible element and particularly that portion at and also preferably adjacent the more readily fusible portion 62 thereof is so made as to contrast as much as is practicable with the 20 white background provided by the surface 66, which includes the surface of the cement body 68, against which it outstands. To this end the fusible element is provided with a coat of paint 70 which contrasts as much as possible with the 25 white background. A dull black paint is preferred, black so that its contrast with the white background is great, and dull so that it will not reflect any material amount of light and reduce the contrast. A colored coating may perhaps be 30 used in place of black as, for instance, red or yellow, but the contrast is not so great and a red or yellow paint soon turns black due to the heating the fusible element. Preferably the black coating occupies about the entire horizontal 35 length 60 of the fusible element that is immediately under the window 42 and at least the more readily fusible section 62 is coated. The top of the fuse thus presents the appearance of a white disc traversed part way by a black stripe, 40 as in Fig. 2, the black stripe standing out prominently in contrast with the white background even in a poorly illuminated locality. The condition of the fusible element may be instantly 45 observed and a break in the element detected 50 visually by a line of white 71, see Fig. 9, traversing the black stripe when the fuse is in its receptacle at some feet from the observer.

The coating 70 need be on only that portion of the fusible element that confronts the window. 55 The remainder of the element and the entire other surface thereof may be uncoated and of its natural finish, which is fairly bright when the fusible element comprises a zinc strip as is customary. The black contrasting coating 70 60 may be applied in any suitable manner as by painting it on by brush or paint rolls or by printing it on by lithography. Preferably a long sheet 72 of the fusible metal, as wide as the fusible element is long, has a lengthwise-extended 65 band 70a of the black coating applied thereto in the proper location and separate fusible elements 26 are severed from the sheet.

I claim:

1. An electric fuse comprising an enclosing 65 casing having a fuse link containing chamber provided with a transparent window, said chamber having a wall under said window that is of a highly light reflecting nature, and a fusible link having a portion interposed between said window and said wall and having in said portion a readily fusible part, said portion on opposite sides of said part having a heat-resistant highly light absorbent surface that confronts said window and traverses said light reflecting surface 70 75

whereby the outline of the dark link is readily visible by contrast upon the light background.

2. An electric fuse comprising an enclosing casing having a transparent window, a fusible element in said casing having a part confronting said window that is black and thereby poorly light reflecting and is adapted to fuse within the length of the black part, said casing having a part that confronts said fusible element part, 10 said casing part being white and more readily light reflecting than said black fusible element part by light entering said casing through said window whereby the outline of said fusible element part appears in strong contrast to the white 15 background provided by said white casing part, said black part being comprised of a surface coating that is resistant to the normal heating of the fusible element.

3. An electric fuse comprising an enclosing 20 casing having a transparent window, a fusible element in said casing having a part that confronts said window, said casing having means located under said fusible element part that provides a white background for said fusible element 25 part when viewed through said window, and said fusible element part having a black heat-resistant coating and thereby presenting a black appearance against said white background, said black fusible element part having an intermediate 30 readily fusible section adapted to fuse and indicate the fused condition by a white line of the white background appearing between the severed black ends of the fusible element.

4. An electric fuse comprising an enclosing 35 casing having a transparent window, a fusible element in said casing having a part that confronts said window, said part being provided with an intermediate readily fusible section, said casing having means located under said fusible element 40 part and readily fusible section that provides a white background for said fusible element part when viewed through said window and when illuminated by light admitted through said window, and said fusible element part on opposite 45 sides of said readily fusible section having a heat resistant surface coating that is relatively unresponsive to said light and does not emit light and presents a black outline of the fusible element against said white background.

5. An electric fuse comprising an enclosing 50 casing having a deep fuse chamber that is open at one end and closed at the other end and has a side wall that slopes inwardly from the open end toward the closed end, a closure for said open 55 end presenting a transparent window which is bigger in cross-section than the cross-section of said chamber at the closed end, said sloping wall and closed end presenting a white surface constituting a background, and a fusible element in 60 said chamber having a part that confronts said window and is between it and said background said part having a heat-resistant coating that presents a dark appearance against said white background when viewed through said window, 65 said dark part having an intermediate relatively fusible section.

6. An electric fuse comprising an enclosing 70 casing having a deep fuse chamber that is open at one end and closed at the other end and has a side wall that slopes inwardly from the open end toward the closed end, a contact member in 75 said lower end, a sealing mass in said closed end over said contact member, a closure for said open end presenting a transparent window which is bigger in cross-section than the cross-section of

said chamber at the closed end, said sloping wall and sealing mass presenting a white surface constituting a background, and a fusible element in 5 said chamber having one end extended through said sealing mass and connected to said contact member and having a part that confronts said window and is between it and said background and has a heat resistant black coating thereon that contrasts sharply with said white background when viewed through said window, said black 10 coated part having an intermediate readily fusible section adapted to melt upon overload and thereby expose a white gap between the severed black ends of the fusible element.

7. An electric fuse comprising an enclosing casing having a deep fuse chamber that is open at one end and closed at the other end and has a side wall that slopes inwardly from the open end toward the closed end, a closure for said open end presenting a transparent window which 20 is bigger in cross-section than the cross-section of said chamber at the closed end, said sloping wall and closed end presenting a white surface constituting a background, and a fusible element 25 in said chamber having a part that confronts said window and is between it and said background and has a heat resistant black coating thereon that contrasts sharply with said white background when viewed through said window, said coating being relatively weakly reflecting 30 and non-light emitting and said background being strongly reflecting to light admitted through said window, said black coated part having an intermediate readily fusible section adapted to melt upon overload and thereby expose a white 35 gap between the severed black ends of the fusible element.

8. An electric fuse comprising an enclosing casing having a deep fuse chamber that is open at one end and closed at the other end and has a 40 side wall that slopes inwardly from the open end toward the closed end, a closure for said open end presenting a transparent window which is bigger in cross-section than the cross-section of said chamber at the closed end, said sloping wall 45 and closed end presenting a white surface constituting a background, and a fusible element having a part that immediately confronts said window and is between it and said background and has an intermediate more readily fusible section, 50 said section and said fusible element part on both sides of said section being provided with a black coating thereon that is resistant to change in appearance by the normal heating of the element and contrasts sharply with said white background when viewed through said window, said coating being relatively weakly reflecting and non-light emitting and said background being strongly reflecting to light admitted through said window, whereby the outline of the coated part 55 stands out prominently against said white background.

9. A plug type electric fuse comprising an insulating casing having a fuse chamber open at one end and closed at the other end, a center 65 contact and a screw-threaded shell carried by said casing, said casing at said open end having an outstanding flange provided with an upper smooth radial wall and a lower wall that is inclined toward said shell and is provided with a 70 series of inclined teeth and interdental chamber venting channels, a transparent plate upon and overlying the end of said casing and the open end of said chamber, and an end cap on said casing over said plate having an inwardly 75

directed flange which underlies and engages said sloping lower wall and said teeth and is capable of yielding in response to pressure in said chamber to relieve said plate from engagement with 5 said upper wall.

10. A plug type electric fuse comprising an insulating casing having a fuse chamber open at one end and closed at the other end, a center contact and a screw-threaded shell carried by 10 said casing, said casing at said open end having an outstanding flange provided with an upper smooth radial wall and a lower wall that is inclined toward said shell and is provided with a series of inclined teeth and interdental chamber 15 venting channels, a transparent plate upon and overlying the end of said casing and the open end of said chamber, and an end cap on said casing over said plate having an inwardly directed flange which underlies and engages said sloping 20 lower wall and said teeth, the inner part only of said end cap flange engaging said sloping end wall and said end cap flange being otherwise spaced from said wall, whereby said end cap flange is capable of yielding in response to pressure 25 within said fuse chamber and permitting said plate to be raised by said pressure away from said upper wall.

11. A plug type electric fuse comprising an insulating casing having a fuse chamber open at 30 one end and closed at the other end, a center contact and a screw-threaded shell carried by

said casing, said casing at said open end having an outstanding flange provided with a smooth radial upper wall and a lower wall that is inclined toward said shell and is provided with a series of inclined teeth and interdental chamber venting channels, a smooth transparent plate bearing upon said upper wall and overlying the open end of said chamber, and an end cap on said casing over said plate having an inwardly directed yieldable flange which underlies and engages said 10 sloping lower wall and said teeth, said channels communicating with the atmosphere under the inner edge of said end cap flange. 5

12. A plug type electric fuse comprising an insulating casing having a fuse chamber open at one end and closed at the other end, a center contact and a screw-threaded shell carried by 15 said casing, said casing at said open end having an outstanding flange provided with a lower wall that is inclined toward said shell and is provided with a series of inclined teeth and interdental chamber venting channels, a transparent plate overlying the end of said casing and the open end of said chamber, and an end cap on said casing over said plate having an inwardly 20 directed flange which underlies and engages said sloping lower wall and said teeth, said end cap flange having indentations in which said teeth are located and by which said end cap is anchored to 25 said casing against rotation thereon. 30
